J. HARTLEY

RAILWAY BOLT

Filed Nov. 3, 1921

FIG. 1

FIG. 2

INVENTOR
By James Hartley
W. W. Williamson Atty.

UNITED STATES PATENT OFFICE.

JAMES HARTLEY, OF PHILADELPHIA, PENNSYLVANIA.

RAILWAY BOLT.

Application filed November 3, 1921. Serial No. 512,460.

To all whom it may concern:

Be it known that I, JAMES HARTLEY, a citizen of the United States, residing at Philadelphia, in the county of Philadelphia and State of Pennsylvania, have invented new and useful Improvements in Railway Bolts, of which the following is a specification.

My invention relates to new and useful improvements in railway bolts, and has for its object to provide an exceedingly simple and effective bolt of novel construction for supporting telegraph or telephone wires along the rails of a railway track, thereby eliminating the necessity of planting poles to support such wires.

Another object of this invention is to provide a railway bolt having a wire holding member formed therewith and having a removable wire holding member mounted on the end of the bolt opposite the member formed with said bolt.

A further object of my invention is to construct the wire holding members of two parts so that they may be separated for attaching the wires thereto or removing them therefrom.

With these ends in view, this invention consists in the details of construction and combination of elements hereinafter set forth and then specifically designated by the claim.

In order that those skilled in the art to which this invention appertains, may understand how to make and use the same, I will describe its construction in detail, referring by numerals to the accompanying drawing forming a part of this application, in which:

40 Fig. 1, is a perspective view of the meeting ends of two rails showing a fish plate and the bolts for holding it in place, one of said bolts being constructed in accordance with my invention and illustrating the manner of its use in supporting wires.

Fig. 2, is an enlarged side elevation of my improved bolt having a portion thereof broken away and sectioned to clearly illustrate the construction.

50 In carrying out my invention as here embodied, 2 and 3 represent the meeting ends of two rails with a fish plate 4 disposed across the joint and held in place by the bolts 5 with nuts 6 thereon and a bolt 7 which embodies my improvement.

The bolt 7 comprises a shank 8 having a head 9 at one end and provided with a reduced projection 10 at the other end. The projection is externally threaded as is also the shank of the bolt at the end adjacent the projection and these threads are preferably right and left hand ones. This end of the bolt has also a longitudinal hole 11 therein for a purpose to be hereinafter described.

With the head of the bolt is integrally formed a wire holding member 12 providing the same is made of one piece but in illustrating one form or construction of my invention I have shown one member or body 13 of the wire holding device formed as an integral part of the bolt with a complimentary or cap 14 as a separate element detachably fastened to the other member in some suitable manner as by screws 15 passing through the coacting ears 16, one of which is formed with each member at each end thereof. Both of the members have arcuate notches which align or coat with one another to form holes 17 for the passage of the wires 18 shown in Fig. 1.

At the other end of the bolt is located the removable wire holding member 18 which also consists of a member or body 13', a complimentary member of cap 14', each of the members having ears 16' through which pass the fastening members 15', the said members also having arcuate notches to produce the holes 17. Thus far the two wire holding members are identical in construction but in the last mentioned one is formed a stem 19 for registration with the hole 11 to removably mount the wire holding member on the bolt and if found desirable said stem may have threads thereon as here shown for threaded connection with the bolt.

When the bolt is in use a nut 20 is threaded thereon and after it has been properly tightened the lock nut 21 is mounted upon the projection 10 of the bolt and if the threads are at opposite directions when the lock nut is jammed against the nut 20 the same will be held against accidental displacement. The lock nut preferably has an outer wall 22 formed therewith so that said lock nut acts as a cap for the end of the bolt and when so made the said outer wall has a hole therethrough for the passage of the stem 19 of the removable wire holding member. I have illustrated both of the wire holding members as having two holes for

the reception of wires but it is to be understood that this member may be decreased or increased according to the conditions encountered in actual railway practice.

5 In practice it is only necessary to place one bolt of my improved construction at the different desired points along a railway track but should the different bolts be placed in staggered relation more than one bolt
10 constructed in accordance with my invention could be used which would permit a greater number of wires to be strung upon one side of a rail. After the bolt has been placed in position the wires are run through
15 the holes or the wires may be set in place and the complimentary members or caps afterward positioned and fastened in place. After the wires are strung the wire holding members will hold them in spaced relation
20 and will also support them to prevent contact with the rail or with the ground.

Of course I do not wish to be limited to the exact details of construction as herein shown as these may be varied within the
25 limits of the appended claim without departing from the spirit of my invention.

Having thus fully described my invention, what I claim as new and useful is:—

In a device of the character stated, a bolt provided with a head and having a longitudinal hole at the opposite end, a body formed integral with the head of said bolt, said body having arcuate notches, ears formed therewith, a cap also having arcuate notches for coaction with the body, the said notches mating to form holes for the reception of wires, ears formed with said cap, and means for detachably fastening the cap to the body, a removable wire holding member comprising a body having arcuate notches, ears formed therewith, a cap having arcuate notches coacting with said body, ears formed with said cap, means for detachably fastening the cap to said body, and a stem formed with the last named body 45 for registration with the longitudinal hole in the bolt to removably mount the last mentioned wire holder on said bolt.

In testimony whereof, I have hereunto affixed my signature.

JAMES HARTLEY.
